UNITED STATES PATENT OFFICE.

RALPH B. ULLOM, OF URBANA, INDIANA, ASSIGNOR TO THE CYCLONE MANUFACTURING COMPANY, OF URBANA, INDIANA.

COOP AND FEEDING PARK THEREFOR.

1,416,531.

Specification of Letters Patent. Patented May 16, 1922.

Application filed April 1, 1921. Serial No. 457,739.

To all whom it may concern:

Be it known that I, RALPH B. ULLOM, a citizen of the United States, residing at Urbana, in the county of Wabash and State 5 of Indiana, have invented certain new and useful Improvements in Coops and Feeding Parks Therefor, of which the following is a specification.

The invention relates to improvements in 10 sanitary coops for the housing of fowls and the like and one of the type to be constructed of sheet metal and which may have associated therewith a park for the feeding of young chicks while the mother hen is confined to the coop proper.

The principal object of the invention is 15 to provide for an improved coop construction involving certain novel features of detachably interlocking the body portion of the same in position on the bottom wall thereof, whereby the coop, as a whole, may be readily transported from one point to another with fowls confined therein, and, at the same time, allow for the removal of 20 the bottom wall for purposes of thoroughly cleaning the same and the entire interior of the coop.

A further object of the invention is to so 25 construct the interlocking means of the front wall portion of the coop, whereby a feeding park may be interlocked therewith to permit restricted freedom of the young chicks exteriorly of the coop with the mother hen confined within the latter.

With the foregoing and other objects in 30 view, the invention resides in the certain novel and useful construction and arrangement of parts as will be hereinafter more fully described, set forth in the appended 35 claims, and illustrated in the accompanying drawings, in which:—

Figure 1 is a perspective view of the coop with the feeding park associated therewith,

Fig. 2 is a vertical longitudinal section 40 through the coop,

Fig. 3 is a vertical transverse section of the same,

Fig. 4 is a fragmentary sectional detail 45 of the adjacent portion of the coop and the feeding park showing the manner of interlocking one with the other, and Fig. 5 is a detail view.

Referring to the drawing, wherein similar characters of reference designate correspond- 50 ing parts in the several views thereof, the

numerals 10 and 10' indicate the side walls, 55 11 and 11' the front and rear walls respectively, and 12 the top wall, of the coop body, the side walls 10 and 10' and the top wall 12 being preferably formed of a single length of sheet metal suitably galvanized to prevent rusting thereof, when exposed to the weather, and which is bent on the proper lines to lend to the structure the configuration as shown. The front and rear 60 walls 11 and 11' are each formed with in-turned flanges 11'' arranged to underly the adjacent edges of the sides and top walls 10, 10' and 12, and have the same secured thereto by means of rivets or other suitable 65 fastenings 13.

The upper central portion of the front wall 11 is formed with sets of openings, one set concentrically of the other, and the openings thereof each arranged in circular series, 70 and mounted for rotary movement on the outer face of the wall is a circular plate or disk 14 in which is formed corresponding sets of openings 14' adapted to be moved into and out of registry with the other of 75 said openings, whereby to control the ventilation of the interior of the coop. In the lower portion of the front wall 11, and at one side of the vertical center thereof, is formed a circular entrance and exit opening 15 which has an inturned flange 15' extending therearound. Associated with the opening 15 are a pair of horizontally swinging closures 16 and 17 which are hinged, as at 16' and 17', respectively to 80 a rod 18 extending vertically at the inner side of the opening, which rod 18 is secured to the front wall 11 at its opposite ends, as by having the latter portions thereof angularly bent and suitably fastened to or in 85 the wall 11, substantially as is shown in Figure 2 of the drawing. These closures 16 and 17 are thus capable of independent opening and closing movement, and the upper closure 16 is of a greater height than 90 the lower closure 17 so as to close a major portion of the exit opening 15, whereby the mother hen will be confined to the coop, while the young chicks will be free to pass in and out of the lower open portion of the 95 latter, when the lower closure 17 is swung to open position for said purpose. For securing the closures 16 and 17 in closed position, suitable pivoted fastenings 19 are provided, while to similarly secure the same in 100

105

110

open position, the pivoted fastenings 20, respectively, are provided.

Referring to Figs. 2 and 3, the opposite lower edges of the side walls 10 and 10' are each formed to provide inturned flanges 21, each formed of a double fold of the metal thereon, and upon these flanges are to be supported angularly bent flanges 22 dependingly formed at the opposite sides of an upwardly depressed bottom wall 23. The rear wall 11' has its lower edge inturned to provide a substantially cylindrical bead 24, the free edge portion 24' of the metal forming this bead being inturned, and disposed vertically downward centrally of the channel of the bead, so as to effect a binding engagement with the downwardly turned rear edge portion 25 of the bottom wall 23. The lower edge of the front wall 11 is formed with an outwardly turned bead 26 of a corresponding formation to that of the bead 24 of the rear wall 11', and which has the free edge portion 26' of the bead metal turned vertically downward of the channel formed in the same. This bead 26 is adapted to rest upon the angularly disposed flange 27 formed in the front end of the bottom wall 23, and this flange formation of the latter is such as to not only function to interlock with the flanges 21 at the beads 24 and 26 of the side and end walls of the body, respectively, but also to admit of the upwardly depressed bottom wall to provide for an air space beneath the coop.

Referring more particularly to Figs. 1 and 2, the numeral 28 designates a feeding park or runway of a suitable wire mesh and of desired configuration as shown therein, the opposite ends of the wire being held in shape by means of suitable metal frames 29 and 29'. The frame 29 is formed of sheet metal bent or folded substantially U-shaped in cross sections, and has the lower member 30 thereof arranged with an outwardly extending horizontal portion 31 which has its free edge portion bent to provide an enclosed portion or beam 32, which is of a suitable cross sectional form to snugly engage in the channel formed in the bead 26 of the front wall 11 of the coop body, whereby the park will be securely connected to and positioned outwardly from the latter by reason of the resiliency of the bead formation. The park 28 is preferably of equal width to that of the coop, and of a height corresponding to that of the exit opening 15, when the upper closure 16 is fastened in position to close the upper major portion of the latter, and the lower closure 17 is fastened in its open position. With this arrangement, the mother hen can be held in confinement within the coop, and the young chicks permitted access to the park for feeding and exercising purposes.

The bottom wall 23 is to be inserted into

position in or to be removed from the coop body, by being canted in a direction transversely of the coop and inclined upwardly thereof and rearwardly from the forward end of the coop body, substantially as is shown in dotted lines in Figs. 2 and 3. When the bottom wall 23 is properly positioned within the coop, the latter may be moved or otherwise transported from place to place without removing the fowls from the same, and when the bottom wall is detached from the body, the entire interior of the coop is readily accessible for cleaning and disinfecting purposes.

Having thus fully described the invention, what I claim is:

1. A coop comprising a body portion of sheet metal open at its lower side, inturned flanges formed at the opposite lower edges of the side walls of the body portion, channeled beads formed at the opposite lower edges of the front and rear walls of the body portion, a bottom portion of sheet metal having a centrally and upwardly depressed portion adapted for insertion into the lower open side of the body portion, flanges formed at the opposite sides and ends of the depressed portion of the bottom portion and adapted for interlocking engagement with the flanges and beads of the body portion, and a feeding park engaging the channeled bead of the front wall of the coop and enclosing the exit opening leading therefrom.

2. The combination with a coop for housing young chicks and having an exit opening in one wall thereof, of a feeding park arranged in abutting relation to the exit end of the coop and enclosing the lower portion of the said exit opening, interlocking means formed at the adjacent ends of the coop and the park whereby the same are detachably connected together, and a closure for the upper portion of the said exit opening.

3. The combination with a coop of sheet metal for housing young chicks, of a feeding park of wire mesh arranged in abutting relation to the exit end of the coop, a channeled bead formed along the lower edge of the exit end of the coop, and means carried at the abutting end of said park for interlocking engagement with said channeled bead.

4. The combination with a coop of sheet metal for housing young chicks, of a feeding park of wire mesh arranged in abutting relation to the exit end of the coop, a channeled bead formed along the lower edge of the exit end of the coop, and a bead formed on the adjacent end of the park adapted for interlocking engagement with the channel of said first mentioned bead.

5. The combination with a coop of sheet metal adapted for housing young chicks and having an exit opening through one wall

thereof, of a feeding park of wire mesh arranged in abutting relation to the exit wall of the coop, and of a height substantially less than one-half of the exit opening there-in, a channeled bead formed along the lower edge of the exit wall of the coop, a bead carried by the adjacent end of the park and adapted for interlocking engagement with the channel of said first mentioned bead, and

10 a closure adapted to close the upper open portion of the exit opening above the adjacent top edge of the park.

6. The combination with a coop for housing young chicks and having an exit opening through one wall thereof, of a feeding park arranged in abutting relation to the wall of the coop and enclosing the lower portion of the exit thereof, and horizontally divided closures for the said exit opening, the upper

15 of said closures being normally closed and the lower thereof open when said feeding park is in position.

7. The combination with a coop for housing young chicks and having an exit opening through one wall thereof, of a feeding park

arranged in abutting relation to the wall of the coop and enclosing the lower portion of the exit thereof, means for detachably connecting said feeding park to the coop, and horizontally divided closures for the said

30 exit opening, the upper of said closures being normally closed and the lower thereof open when said feeding park is in position.

8. The combination with a coop of sheet metal for housing young chicks and having an exit opening through the front wall thereof, of a feeding park extending the full width of the front wall of the coop and enclosing the lower portion of the exit thereof, interlocking means formed at the lower

35 abutting edges of the coop and feeding park for detachably securing the same together, and horizontally divided closures for the said exit opening, the upper of said closures being normally closed and the lower thereof

40 open when said feeding park is in position.

In testimony whereof, I affix my signature hereto.

RALPH B. ULLOM.
